Attn:

UNITED STATES PATENT OFFICE.

SERENUS M. COLBURN, OF MINNEAPOLIS, MINNESOTA, ASSIGNOR TO FLOUR CITY ORNAMENTAL IRON WORKS, OF MINNEAPOLIS, MINNESOTA, A CORPORATION OF MINNESOTA.

DESIGN FOR A STREET-LAMP.

No. 39,759.

Specification for Design.

Patented Jan. 12, 1909.

Application filed October 29, 1908. Serial No. 460,166. Term of patent 7 years.

To all whom it may concern:

Be it known that I, SERENUS M. COLBURN, a citizen of the United States, residing at Minneapolis, in the county of Hennepin, State of Minnesota, have invented a new, original, and ornamental Design for Street-Lamps, of which the following is a specification, reference being had to the accompanying drawing, forming part thereof.

The figure is a front elevation of a street lamp showing a new design.

I claim:

The ornamental design for a street lamp as shown.

SERENUS M. COLBURN.
